[57] CLAIM

The ornamental design for a table, as shown and described.

DESCRIPTION

FIG. 1 is a top plan view of a table showing our new design and the surface configuration thereof;

FIG. 2 is a front/side view of a table showing our new design;

FIG. 3 is a bottom plan view of a table showing our new design;

FIG. 4 is a top plan view of a modified form of the table shown in FIGS. 1-3 but wherein the top is round rather than square; and

FIG. 5 is a top plan view showing a second modified form of the table disclosed in FIG. 1 but wherein the top is rectangular rather than square.

FIG. 2

FIG. 1

FIG. 3

FIG. 4
